• Lorenzo Dow
Yellow Patent

The schedule referred to in these Letters Patent and making part of the same containing a description in the words of the said Dow of his improvement in Medicine.

1. Take nine pounds of genuine Boston salts, dissolved in eight boiling water, the whole making eight quarts to which add the extract of Blood root, sanguinaria, say four ounces. 2. Take one pound fine salts Nitre dissolved in boiling water making eight ounces sulphuric acid of the best quality, the whole making four quarts all of which must be stored with a wood, or stick and when cool and the same with the above Boston salts and Blood root solution, which will constitute Dow's family Medicine in its full strength in its concentrated state. The whole process must be performed in stone or earthen vessels, and afterwards preserved in glass. One or two table spoons full in a half pint of cold water or less quantity of each may be taken once in two hours until it operate freely. This medicine has been found of general utility and efficacy in all those disorders called a bilious and effections of the liver exceeding common credibility even in many cases wherein a purgative course of mercurials have been used in vain, hastening a convalescence in Disease, a speedy relief is obtained.
